UNITED STATES PATENT OFFICE

2,691,548

DEVICE FOR SPRAYING A GAS-CONTAINING FLUID

Otto Feucht, Backnang, Wurttemberg, and Just Söhlemann, Schonaich, Wurttemberg, Germany

Application October 8, 1952, Serial No. 313,740

Claims priority, application Germany October 9, 1951

9 Claims. (Cl. 299—95)

1

This invention relates to a spray apparatus and is particularly concerned with a device for spraying a gas-containing fluid, by way of example for treating and scavenging body cavities, particularly the mouth with the teeth, wounds, mucous membranes and sickened skins.

For preventing and combating different illnesses of the body cavities, particularly the mouth cavities including the teeth and cleansing the same for treating wounds and certain skin diseases physicians suggest to spray fluids mixed or saturated with gases, particularly carbonic acid, and in which different disinfectants and therapeutic substances are dissolved or admixed, into the body cavity, on the wound or the skin with a fine jet pressure. The gases admixed to the fluid and the mechanical irritation will bring about a more intense hyperaemia of the concerned tissues, whereby the effect of the disinfectants and the therapeutic substances will substantially be increased.

In the design of devices for spraying medically efficient gas-containing fluids several conditions must be considered. All parts of the device which come into contact with the fluid must be developed so that they cannot be attacked by the fluid. As, for instance in the treatment of gums for swelling down the gums, caustic chemicals are often used which attack several metals, one must lay particular stress on no metals dissolving in the fluid, particularly in the form of salts, and which may be detrimental to health, being used as materials for parts which come into contact with the fluid.

The device must be so constructed as to guarantee a steady jet pressure even during an extended treatment.

Several devices for spraying fluid were produced destined for domestic use. It has turned out, however, that the devices have not yet come into general use. The reason of this failure is in the fact that these devices are either too difficult to handle or that their purchase or their management are too costly or that other disadvantages have prevented people from purchasing.

It is accordingly an object of this invention to provide an improved spray for the care of the mouth and the teeth.

Another object of the invention is to provide a spray of novel design which is simple to operate and to clean, and which will cheaply be produced and purchased.

It is another object of the invention to provide a spray whose parts are substantially made of

2

transparent materials, so that the taking away of impurities being the culture media for bacteria is made easier, and uninitiated persons, such as children can be made to keep the device hygienically clean.

It is another object of the invention to provide a spray with a tablet holder of novel design, in which tablets are put which dissolve in the water the spray is filled up with, and produce carbonic acid especially.

Another object of the invention is to provide a spray whose parts contacting with the fluid are made of a material, preferably of such plastics as not to be attacked by any of the concerned chemicals of the fluid dissolved in the same.

Another object of the invention is to provide a spray whose parts made of thermoplastic material are transparent, break-proof and chemically inert.

It is another object of the invention to provide a spray whose parts are so designed as to be produced cheaply in mass production by casting and die-casting and to be assembled easily.

Another object of the invention is to provide a spray whose mouth piece is surrounded by a funnel so that particles of the sprayed fluid mixture rebounding from the spot of treatment are intercepted, and the mucous membranes pockets of the body cavities will be kept off the orifice.

Another object of the invention is to provide a spray with a quick-action seal so that during the interval between the filling of the sprayer bottle comprising the entering of the gas-producing chemicals and the gas-tight sealing substantially no gas pressure arises in the sprayer bottle, which would render the sealing more difficult and bring about a reducing of pressure.

Another object of the invention is to provide a spray whose quick-action lock is so designed that it can be operated with one hand only in order to allow an easy handling by invalidated persons, too.

Another object of the invention is to provide a spray whose valve and feed lines to the valve and to the mouth piece are so designed that hardly any energy of pressure is lost because of the friction of the fluid on the walls, that is to say that when operating the spray the compressed fluid mixture flows slowly and steadily to the mouth piece, and only there the pressure of the fluid is converted into kinetic jet energy.

Another object of the invention is to provide a tablet holder at the end above the container bottom of the spray of the tube dipping into the fluid, being so arranged and designed that in it

the ingredients acting therapeutic and disinfectant and the gas-developing substances can easily be inserted in a certain mixture with tablets containing binding agents or none, taste-improving substances, and that the tablet holder during the dipping into the fluid intercepts till the final sealing of the device the gasses developed by the tablets with the filling fluid of the spray, preferably water, and that it deposits not dissolved solids of the fluid flow flowing to the 10 valve.

It is another object of the invention to provide a spray with a valve to be operated by hand for sealing and opening the exhaust port of the fluid of such a design as to open the exhaust port if the gas pressure in the container exceeds an admissible top limit.

The invention is described more fully herein-after with reference to a preferred embodiment of the same illustrated in the drawings. In the 20 drawing is shown:

Fig. 1 a schematic view of a spray constituting a preferred embodiment of the invention,

Fig. 2 a plan of the spray according to Fig. 1,

Fig. 3 a longitudinal section across the spray 25 along the line I—I in Fig. 2,

Fig. 4 a fragmentary sectional view of the spray taken along the line II—II in Fig. 2,

Fig. 5 a view of the tablet holder seen from the 30 bottom,

Fig. 6 a fragmentary sectional view through the tablet holder taken along the line V—V in Fig. 5.

The neck of a bottle-like container 1 widening toward the bottom is provided with a flange 2 encircling an opening of the container being so wide that the container 1 can easily be cleansed and filled with a fluid. The container 1 is made of transparent and unbreakable plastics which will hardly be attacked or corroded by substances used in medicine for the therapeutic and disinfectant purposes preferably of plastics, such as polymethacryl acid ester or polystyrol. The size of the container 1 is so designed that on the one hand it can receive the fluid quantities usual in medicine for washing body cavities, particularly the mouth, about 50—1000 cm.³, but on the other hand will not be unwieldy. The opening of the container 1 surrounded by flange 2 is sealed by top part 4 to which two stirrups 5 of a stirrup lock are linked. In the locking position the stirrups 5 engage with noses 6 into the slightly chamfered bottom side of flange 2 and press the top part 4 to the top side of flange 2. In order to guarantee a gastight sealing a sealing ring 7 is provided which is kept in its position by a ring 8 encircling it at the top part 4. The sealing ring 7 has two lips 9 directed inward, which, if there is in container 1 an excess pressure in relation to the atmospheric pressure, on the one hand contact the flange 2, on the other hand the top part 4, and thus seal the container 1 gastight.

The top part 4 consists of two parts, the top member 11 and the bottom member 12. The surface of the bottom member 12 is provided with two notches 14 preferably of a rectangular cross section adapted for receiving the hooked ends 13 of the locking stirrups 5. In the side walls of the top member 11 of the top part 4 recesses 15 are provided corresponding notches 14 of the bottom member. The height and width of the recesses 15 are so sized that the hooked ends 13 have such a clearance that, on the one hand, each of the locking stirrups 5 cannot fall off the corresponding notch 14 and would thus be loosened from the top part 4, on the other hand,

however, the locking stirrups 5 are allowed a sufficient clearance for disconnecting the noses 6 from engaging with flange 2.

For connecting the top member 11 with the bottom member 12 there are two vertical holes 16' in the top member 11 alining with two holes 16' provided in the bottom member 12. Near the bottom end of each hole within the bottom member 12 a nut 19 is cast in so as to receive a bolt 16 passing through the top member for tightening both parts.

The top member 11 and the bottom member 12 represent bodies substantially turned cylindrically. Through the bottom part 11 a concentric bore passes, which is twice abruptly enlarged from its top end to its bottom end so as to form a top shoulder 21 and a bottom shoulder 22 within the bore. In the bottom part there is likewise provided a concentric bore which extends from the bottom end to the top end and is twice abruptly enlarged so as to form a shoulder 23 and a shoulder 24.

In the shoulder 22 there is a guide disk 26 inserted made of metal or preferably of hard plastics for a valve pin 27.

At the valve pin 27 a disk 28 is fixed. A spring 29 supports itself, on the one hand, on the disk 28, on the other hand against the shoulder 21 and presses the valve pin downward till the valve cone 31 mounted on the valve pin 27 is seated on the shoulder 23, and thus closes the bore of the bottom member 12. In an opening passing in the top member 11 from the outside wall to the central bore with a substantially rectangular cross section an arm 32 of a hand lever 33 is arranged. The bottom of the arm 32 is curved and in contact with the top surface of the bottom member 12 on which it can devolve. The end of the arm 32 is designed as eye 34 encircling the valve pin 27.

If the hand lever 33 is pressed against the container 1, the arm 32 devolves on the top surface of the bottom member 12 pressing the disk 28 to the top with an eye 34 against the action of the spring 29. The valve pin 27 will glide axially to the top in the bore of the top member 11 and in the guide disk, whereby the valve cone 31 will be retracted from the shoulder 23.

In the shoulder 24 of the bottom member 12 50 a sealing ring 36 is inserted, which, if the top member 11 is fixed on the bottom member 12 is held by the guide disk 26, so that the collar-like or in the cross section lip-shaped inside edge of the packing ring 36 can under the pressure of 55 gases seat on the valve pin 27 which thus closes the bore of the bottom member gastight against the bore of the top member.

In the bore of the bottom member 11 a tube 41 is fixed extending into the container 1 in alignment with the bore. At the end of the tube 41 60 extending into the container 1 a tablet holder 42 is arranged.

The tablet holder 42 consists of two substantially cylindrical hollow bodies 43 and 44. The hollow body 43 is within the hollow body 44 and with the common axis vertically disposed so as to form a slit-like ring space 46 adapted to prevent undissolved parts of the tablets from entering the ring space 46. The hollow body 43 is secured in proper distance at the hollow body 44 by means of fillet 47. The two cylindrical hollow bodies 43 and 44 are provided in the upper ends with front walls 48, 49 being substantially spaced as the cylindrical hollow bodies 43 and 44. The space between the front walls 48, 49

and the ring space 46 between both cylindrical hollow bodies are in communication with one another and with the tube 41. The front walls 48 and 49 are provided with openings 51 not directly communicating with the ring space 46. The openings 51 allow the space of the inside cylindrical hollow body 43 to communicate with the space of the container 1 above the front wall 49. The inside wall of the cylindrical hollow body 43 is provided with elastic bar-shaped cutters 52 adapted to fix the tablets 54 set into the cylindrical hollow body 43.

The bottom member 12 of the top part 4 has a transverse hole 55 running up to the concentric central bore in the bottom member. In the transverse hole a tube 56 is fixed, whose end lying outside the top part 4 is provided with a funnel-shaped mouth piece 57. The funnel-shaped mouth piece 57 encircles the nozzle-shaped opening 58 of the tube 56.

The effect and the operation of the spray is the following:

The operator appropriately leads one hand along the container 1 and presses the stirrups 5 with their sticking out handles 10 off the container 1. By swinging the stirrups 5 the noses 6 are disconnected from their locking position with the bottom surface of the flange 2. As soon as the hand is furthermore brought to the top, the hooked ends 13 put on the inside walls of the passage 15 within the top member 11, whereby a further swinging motion of the stirrups 5 is prevented. Thus the top part 4, by putting the hand on the handles 10, can be lifted off the container 1 that is to say off the opening of the locking with one pull. Now tablets 54 containing therapeutic and disinfectant ingredients and gas-developing ingredients, are introduced into the tablet holder where they are held back by the cutters 52. Now the container 1 is filled with water and the top part 4 put on the container 1, the tablet holder 42 dipping into the water contained in the container 1. As soon as the tablets 54 come in contact with the water, the gas-developing ingredients of the tablets dissolve in the water and immediately gas will be developed. Lest in the container 1 a gas pressure should arise rendering the locking of the container difficult, the tablet holder 42 is so designed that the gases first developed press the water out of the tablet holder. When the top part 4 is seated on the container, the locking stirrups 5 are compressed, the noses 6 engaging in the bottom side of the flange 2.

The gases developed within the inside hollow body 43 escape only slowly by way of the opening 51 into the space of the container 1 and saturate the water in the container 1 which in the meantime was enriched with the dissolving therapeutic and disinfectant substances. If now the hand lever 33 is pressed against the container 1 the opening at the shoulder 23 is freed by the valve cone 31, whereby the fluid exposed to the pressure produced by the gases generated within the container gets to the mouth piece by way of the split-like ring space 46, the tube 41, the concentric bore in the bottom member 12 and by way of the transverse hole leading to the outside and flowing out into the concentric bore, the tube 56, and is sprayed out there in a fine jet. As soon as the hand lever 33 is released, the spring 29 presses the valve cone 31 against the opening flowing out at the shoulder 23 and closes this opening till the inner pressure becomes so high that it can by itself lift off the valve cone 75

31 from the opening against the action of the spring 29. The spring is given such a tension that the valve cone 31 will be released just when the pressure within the container should accede an admissible limit.

While the invention has been described in considerable detail with reference to a preferred embodiment thereof, it will be understood that variations and modifications may be made. For instance some of the specified features may be substituted by others of equivalent effects, and different combinations of the features may be achieved within the spirit and scope of the invention as described hereinabove and illustrated in the drawings and as defined in the appended claims.

What is claimed is:

1. A device for spraying a gas-containing fluid comprising a bottle-like container for receiving a fluid adapted to develop gases together with gas-developing substances, a flange on the said container this flange being arranged around an opening of the container, a top part adapted to close the said opening by contact with the flange, locking means adapted to press down the top part on the said flange, packing means inserted between the top part and the flange, a tube fixed at the top part and arranged in alignment with a bore of the top part, the one end of this tube being arranged above the bottom of the container, a second tube fastened at the top part and arranged in alignment with a second bore of the top part and in direction transverse to the first-named tube and having its outlet outside the top part, a valve adapted to connect both tubes and arranged in the top part and automatically movable away from its valve seat by excess pressure in the container, spring means adapted to close the valve against the action of the gas pressure existing in the container, and means operated by hand and adapted to open the valve against the action of the said spring means.

2. A device for spraying a gas-containing fluid comprising a bottle-like container for receiving a fluid adapted to develop gases together with gas-developing substances, a flange on the said container this flange being arranged around an opening of the container, a top part adapted to close the said opening, locking means adapted to press down the top part on the said flange, rigid means being provided adapted to fix the top part at a distance from the flange, elastic sealing means inserted between the top part and the flange said elastic means consisting of a ring provided at its inner surface with lips adapted to be expanded by the pressure of the gases developed in the container, the upper of these lips being adapted to be put against the flange, a tube fixed at the top part and arranged in alignment with a bore of the top part, the one end of this tube being arranged above the bottom, a second tube fixed at the top part and arranged in alignment with a second bore of the top part and in a direction transverse to the first-named tube, and having its flowing out outside the top part, a valve adapted to connect both tubes and arranged in the top part, spring means adapted to close the valve against the action of the gas pressure existing in the container, and means operated by hand and adapted to open the valve against the action of the said spring means.

3. A device for spraying a gas-containing fluid comprising a bottle-like container for receiving a fluid adapted to develop gases together with gas-developing substances, a flange on the said con-

tainer this flange being arranged around an opening of the container, a top part adapted to close the said opening, locking stirrups having hinge joints with the top part, a nose at each of the said locking stirrups arranged so as to lock the respective locking stirrup under the flange and to press the top part on the said flange, elastic sealing means inserted between the top part and the flange, a tube fixed at the top part and arranged in alignment with a bore of the top part, the one end of this tube being arranged above the bottom of the container, a second tube fixed at the top part and arranged in alignment with a second bore of the top part and in a direction transverse to the first-named tube and having its flowing out outside the top part, a valve adapted to connect both tubes and arranged in the top part, spring means adapted to close the valve against the action of the gas pressure existing in the container, and means operated by hand and adapted to open the valve against the action of the said spring means.

4. A device for spraying a gas-containing fluid, comprising a bottle-like container for receiving the fluid, a flange at this container, this flange being arranged around an opening of the container, a top part adapted to close up the said opening, locking means adapted to press down the top part on the said flange, elastic sealing means inserted between the top part and the flange, a tube fixed at the top part and arranged in alignment with a bore of the top part, the one end of this tube being arranged above the bottom of the container, means arranged on the said tube and adapted to hold tablets containing substances adapted to develop gases together with the said fluid, a second tube fixed at the top part and arranged in alignment with a second bore of the top part and in a direction transverse to the first-named tube and having its flowing out outside the top part, a valve adapted to connect both tubes and arranged in the top part, spring means adapted to close the valve against the action of the gas pressure existing in the container, and means operated by hand and adapted to open the valve against the action of the said spring means.

5. A device for spraying a gas-containing fluid comprising a bottle-like container for receiving the fluid, a flange on this container, this flange being arranged around an opening of the container, a top part adapted to close up said opening, locking stirrups having hinge joints with the top part, a nose at each of the locking stirrups arranged so as to lock the respective locking stirrup under the flange and to press the top part against the said flange, a tube fixed at the top part and arranged in alignment with a bore of the top part, the one end of this tube being arranged above the bottom of the container, means arranged on the said tube and adapted to hold tablets containing substances adapted to develop gases together with the said fluid, a second tube fixed at the top part and arranged in alignment with a second bore of the top part and in a direction transverse to the first-named tube and having its flowing out outside the top part, a mouth piece substantially funnel-shaped and fixed on the free end of the second-named tube and arranged around the flowing out of the tube, a valve adapted to connect both tubes and arranged in the top part, spring means adapted to close the valve against the action of the gas pressure existing in the container, and means operated by hand and adapted to open

the valve against the action of the said spring means.

6. A device for spraying a gas-containing fluid, comprising a bottle-like container for receiving a fluid adapted to develop gases together with gas-developing substances, a flange on this container, said flange being arranged around an opening of the container, a top part adapted to close the said opening and consisting of a top and a bottom member, means for connecting the top and the bottom member, locking stirrups adapted to press the top part against the flange, the side surface of the top member of the top part having recesses in a number corresponding to those of the locking stirrups, the bottom member of the top part at its surface adjacent to the said top member having recesses corresponding to those of the top member and substantially shaped with rectangular section a fillet between each recess on the top surface of the bottom member of the top part and the side surface said bottom member being rounded off at its surface and adapted to serve as a support for the respective locking stirrup each of the locking stirrups being hooked at its one end and adapted to enter the respective recesses of the top member and the bottom member of the top part and to rest with the inner surface of the hook upon the respective fillet of the bottom member of the top part, the height of each hook being approximately that of two corresponding recesses, thus each locking stirrup having hinge joints with the top part and adapted to be held by the top part against loosening, a nose at each of said locking stirrups, each nose being arranged so as to lock the respective locking stirrup under the flange and to press the top part against the said flange, elastic sealing means inserted between the top part and the flange, a tube fixed at the top part and arranged in alignment with a bore of the top part, the one end of this tube being arranged above the bottom of the container, a second tube fixed at the top part and arranged in alignment with a second bore of the top part and in a direction transverse to the first-named tube and having its flowing out outside the top part, a valve adapted to connect both tubes and arranged in the top part, spring means adapted to close the valve counter the action of gas pressure existing in the container, and means to be operated by hand and adapted to open the valve counter the action of the said spring means.

7. A device according to claim 4, wherein the means adapted to hold tablets and connected to one of the tubes are arranged at the end of the said tube above the bottom of the container and consist of two substantially cylindrical hollow bodies arranged one within the other and with their common axis vertically so as to form a split-like ring space adapted to prevent undissolved parts of the tablets to enter the ring space, said cylindrical hollow body having front walls at their upper ends substantially spaced as the cylindrical hollow bodies, and of means for holding the cylindrical hollow bodies in spaced relation, the space between the front walls and the said ring space between both cylindrical hollow bodies being in communication with each other and with the said tube, both front walls being provided with communicating openings so as to allow the space of the inner cylindrical hollow body to communicate with the space of the container above the front walls, and elastic bar-like means arranged longitudinally on the inner surface of the inner cylindrical hollow body in

order to form cutters adapted to hold tablets inserted into the inner cylindrical hollow body.

8. A device according to claim 5, in which the bore of the top part, which is in alignment with the first tube, has in a distance from the bottom surface of the top part a larger diameter than the section of the bore which directly follows the bottom surface of the top part, the shoulder formed by the two bore sections of different diameters is adapted to serve as a valve seat, a valve cone is provided and adapted, when seating on the valve seat, to close the bore, a valve pin is connected to the valve cone and centrally disposed within the bore, a recess concentrically disposed to the bore is provided in each of the adjacent surfaces of the top member and bottom member of the top part, a sealing element made of elastic material is arranged in the said recess of the top surface of the bottom member of the top part, the said sealing element consisting of a disk and a cone integral with the disk and arranged so as to be directed into the section of the bore housed in the bottom member of the top part, a ring is arranged within the recess of the bottom surface of the top member of the top part, said ring being provided with a border at its circumference adapted to press the disk of the sealing element, the sealing element and the ring having each a centrally arranged hole to receive the valve pin, the cone of the sealing element, when under pressure of the fluid, being adapted to enclose the valve pin tightly, the second bore of the top part being arranged to flow out into the first bore between the sealing element and the valve face, the bore in the top member of the top part opposite the surface adjacent to the bottom member of the top part, a bottom member integral with the top member of the top part, this bottom member being provided with a hole adapted to guide the valve pin, a locking disk secured to the valve pin between the bottom member and the ring, a coil spring is arranged around the valve pin between the bottom member and the locking disk, the said coil spring being adapted to press the valve cone against the valve seat counter the pressure developed in the bottle, an opening provided at the bottom surface of the top member of the top part and extending from the bore to the side surface of the said top member, a bent lever one arm of which has a curved section, this arm being disposed within the said opening and adapted to roll off with the curved section on the top surface of the bottom member of the top part, the said arm having means at its end adapted to encircle the valve pin below the locking disk.

9. A device for spraying a gas-containing fluid, comprising a bottle-like container made of plastic materials, a flange integral with the container and arranged around an opening of the container, a top part made of plastic materials adapted to close the said opening and consisting

of a bottom member and a top member, means for connecting the top member and the bottom member, locking stirrups made of plastic materials having hinge joints with the top part and being adapted to press the top part against the said flange, the side surface of the top member of the top part being provided with recesses in a number corresponding to those of the locking stirrups, the bottom member of the top part with its top surface adjacent to the said part being provided with recesses in a number corresponding to those of the top member and having substantially rectangular sections, a fillet between each recess of the top surface of the bottom member of the top part and the side surface of the bottom member being rounded off at its top surface and adapted to serve as a support for the respective locking stirrup, each locking stirrup being hook-shaped and adapted to enter the respective recesses of the top member and the bottom member of the top part and to rest with the inner surface of the hook upon the respective fillet of the bottom member of the top part, the height of each being approximately that of the corresponding recesses thus each locking stirrup having hinge joints with the top part and adapted to be held by the top part against loosening, a nose integral with the said locking stirrup, each nose being arranged so as to lock the respective locking stirrup under the flange and to press the top part against the said flange, elastic sealing means inserted between the top part and the flange, a tube made of plastic materials and fixed at the top part and arranged in alignment with a bore of the top part, the one end of this tube being arranged above the bottom of the container, means made of plastic materials and arranged on the said tube and adapted to hold tablets containing substances adapted to develop gases together with the said fluid, a second tube made of plastic materials and fixed at the top part and arranged in alignment with a second bore of the top part and arranged in a direction transverse to the first-named tube and having its flowing out outside the top part, a mouth piece made of plastic materials substantially funnel-shaped and fixed at the free end of the second-named tube and arranged around the flowing out of the tube, a valve adapted to connect the two tubes and arranged in the top part, spring means adapted to close the valve counter the action of the gas pressure existing in the container, and means operated by hand and adapted to open the valve counter the action of the said spring means.
